UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

DRAINAGE-EXCAVATOR.

1,168,784.

Specification of Letters Patent. Patented Jan. 18, 1916.

Application filed December 28, 1910. Serial No. 599,665.

To all whom it may concern:

Be it known that I, MORTON G. BUNNELL, a citizen of the United States of America, and resident of Chicago, Cook county, Illinois, have invented a certain new and useful Improvement in Drainage-Excavators, of which the following is a specification.

My invention relates to drainage excavators of that general type in which an excavating bucket or scoop is arranged to travel upon a track or runway having one or more bends or angles in the length thereof, necessitating one or more changes in the direction of travel of the said bucket or 15 scoop during the use of the same for excavating purposes.

Prior to my invention, it was customary to provide one or more cables or chains or other similar flexible connections for operating the 20 said bucket or scoop, and to arrange the said cables or chains in such manner that they traveled upon sheaves or other anti-friction devices disposed at intervals along the length of the track or runway, whereby the said 25 cables or chains were guided and held to a line or direction of travel approximately the same as that of the bucket or scoop. Obviously, however, it was impossible to arrange the said cables or chains in such manner 30 that they would exert a direct and straight forward pull on the bucket or scoop throughout the entire range of movement of the latter, inasmuch as the said sheaves or anti-friction devices for guiding the cables 35 or chains could not be arranged directly in the path of travel of the bucket or scoop, whereby more or less side draft was always exerted upon the said bucket or scoop, particularly at the curves or angles in the runway, the cables or chains at these places often departing considerably from the direction 40 of the runway. In other words, the arrangement was often such that the cables or chains did not follow the line or direction 45 of the runway in rounding a curve or turning a corner, but to the contrary would take a short cut from one point to another inside of such curve or angle, thus increasing the side draft on the bucket or scoop, and causing it to bind and run hard in the runway. With such arrangement, provision had to be 50 made for guiding the bucket or scoop past the sheaves or other devices for guiding the cables or chains. So far as I am aware, this

always resulted in more or less side draft on 55 the bucket—that is to say, a pull on the bucket in a direction at an angle to the direction of the runway, whereby, as explained, the bucket would tend to cramp or bind in the runway during the use of the same for 60 excavating purposes.

The principal object of my invention, therefore, is the provision of an improved construction and arrangement for eliminating side draft on the bucket or scoop as it 65 travels along the runway of an excavator of the foregoing general character.

A special object of my invention is the provision of an arrangement whereby the operating cables or chains for the bucket or 70 scoop are provided with wheels or other devices carried at different points in the length thereof and adapted to travel in the same runway in which the said bucket or scoop is arranged to travel, thus making the direction 75 or line of travel of the said cables or chains coincident with the line of travel of the bucket or scoop throughout the entire length of the runway, and thus entirely eliminating side draft, thereby enabling the 80 cables or chains at all times to exert a straight forward pull on the bucket or scoop while the latter is traveling along the runway.

It is also an object of my invention to provide an improved construction and arrangement whereby the structure of the runway is made stronger than heretofore, and whereby the up and down adjustment of the runway does not involve the lifting and lowering of 90 as much bulk and weight as heretofore.

It is also an object to provide certain details and features of improvement and combinations tending to increase the general efficiency of a drainage excavator of 95 this particular character.

To the foregoing and other useful ends, my invention consists in matters hereinafter set forth and claimed.

In the accompanying drawings—Figure 100 1 is a front or end elevation of a drainage excavator embodying the principles of my invention, showing the same with the runway thereof raised out of the ditch or excavation. Fig. 2 is a view similar to Fig. 1, 105 but showing the runway of the machine lowered into the ditch or excavation, and showing the buckets in position to load and

unload in their back and forth travel across the ditch—that is to say, as they travel back and forth from one side of the ditch to the other. Fig. 3 is a detail view of a portion of one of the operating chains for the excavating buckets, showing one of the wheels with which the same is equipped. Fig. 4 is a side elevation of one of the excavating buckets or scops—that is to say, one of the two excavating buckets with which the machine is equipped, as shown in Figs. 1 and 2. Fig. 5 is a detail cross section on the line 5—5 in Fig. 1, showing the construction of the two track or double runway, and showing the spreader rods by which the two bucket operating chains are spaced apart, and showing the wheels by which the said operating chains are supported in the tracks of the runway.

As thus illustrated, the body of the machine A may be of any suitable, known or approved construction. As shown, it is provided with wheels *a* adapted to travel on tracks *a'* at opposite sides of the ditch or excavation B. In this way it will be seen that the machine is of that type in which the body straddles the ditch or excavation, as the excavator moves along, and in which provision is made for dumping the displaced or excavated dirt at each side of the ditch. The body of the excavator is provided with an upright frame C consisting of two upright guide members *c* spaced apart and rigidly connected by cross rods or beams *c'*, *c''*, their lower ends being connected to the platform or body of the machine. Supported in part at least by the cross bar *c''* is a superstructure or frame D which is provided at its upper end with a bracket bearing *d*, and with a pair of sheaves *d'*, it being observed that these sheaves are mounted to rotate about a horizontal axis extending longitudinally or in the direction of the ditch. It will be seen that the frame or superstructure D is also braced and held in place by rods or beams *d''*, which have their lower ends secured on the body or platform A, and which have their upper ends suitably secured to the bracket plate *d*, as illustrated. A pair of upright channel irons E are arranged to slide up and down and upon the guides *c*, and are connected together near their upper ends by a cross bar *e*. That portion F of the runway which is substantially U-shaped or V-shaped in character, and which determines the cross sectional contour of the ditch, has its outer ends secured to the outer ends of the beam or cross bar *e*, and has its intermediate portion secured to the lower ends of the vertically disposed channel irons E, whereby a rigid frame is provided which is adapted to slide up and down on the frame-like structure rigidly supported on the platform or body of the machine. The outer or

pivoted sections G and H of the runway have their lower or inner ends pivoted at *g* and *h* to the outer ends of the middle section F of the runway, and have their outer ends provided with sheaves *g'* and *h'*, as illustrated. Each outer swinging or pivoted section of the runway, as well as the middle section thereof, is composed of two parallel channel irons, as for example *g''* and *g'''*, as shown in Fig. 5, whereby a double track is provided throughout the length of the runway thus constructed.

Any suitable means may be provided for spacing apart and rigidly holding in position the two sides of the section F of the runway. The two sides of the outer sections are, however, preferably rigidly connected together by arches composed of transverse channel irons secured to the upper ends of the angle irons, the lower ends of which latter are rigidly secured to the runway. For example, as shown in Fig. 5, the outer section G of the runway has its sides provided with angle irons *g''*, the upper ends of which angle irons are rigidly connected together by channel irons *g'''*, thus providing two arches which effect connect together the two sides of the runway. Thus the two tracks or two sides of the runway are definitely and accurately spaced apart throughout the length thereof, providing two channels which face each other and provide tracks or ways for the wheels of the operating chains. As shown, there are two operating chains I, one at each side of the runway, and these two chains are connected at intervals by spreader rods *i*, each rod being provided at its outer end with a wheel *i'*, (see Figs. 3, 4 and 5). In this way the two parallel operating chains connected by their spreader rods form a flexible structure which is ladder-like in form, and the wheels *i'* of which travel in the channels or grooves of the channel irons *g''*, *g'''*, as shown in Fig. 5. One end of the structure formed by the two chains and their spreader rods is attached to an operating cable J which runs over the sheave *h'* and one of the sheaves *d'*, which then descends and has its lower end wound upon the drum K, which latter is operated by an engine on the platform or body of the machine, in the usual and well known manner. The other end of the two chains is connected with an operating cable L which runs over the sheave *g'* and the other of the sheaves *d'*, and which then descends and has its lower end wound upon the drum M, the latter being also supported on the platform or body of the machine and driven by the said engine. It will be understood that the two drums are controlled by the operator through the medium of suitable mechanism in the usual and well understood manner. With this arrangement one of the said

cables can be wound in while the other is paid out, which will result in causing the two chains with their spreader rods and wheels to travel along the runway in one direction. A reversal of the drums will then cause the chains to travel in the opposite direction. At a suitable distance apart and disposed near the middle of the two operating chains, there are two excavating buckets 5 N and O, which buckets may, for the broader purposes of my invention, be of any suitable, known or approved character. As shown, however, these buckets are of simple form, being scoop-like in shape, and are provided with front and rear wheels, as for example the wheels n and n' shown in Fig. 4. It will also be seen by reference to this same figure of the drawings that the chains are attached by a single pivotal point to the 10 sides of the bucket, as for example at n², whereby when the wheels of the bucket are caused to depart from the regular line of travel the bucket will be tilted to a dumping position. In Fig. 2 the bucket N is 15 shown in dumping position, while the bucket O is shown in position to load, the said bucket O being illustrated as just starting on its downward course across the ditch. With such arrangement it is necessary for 20 one bucket to dump at one side of the ditch, and for the other bucket to dump at the other side of the ditch, it being observed that the mouths or open ends of the two buckets face outwardly and in opposite directions. For this purpose the runway section G is provided with a deflection or bend 25 g⁶ near the upper end thereof, while the runway section H is provided with a similar deflection or bend h² near the upper end 30 thereof. When the wheels of the bucket N run into the bend or deflection g⁶, the bucket is instantly thrown or tilted into the position shown in Fig. 2, and the load is discharged from the mouth thereof onto the 35 embankment at that side of the ditch. On the other hand, when the bucket O is caused to travel across the ditch, and when its wheels encounter the bend or deflection h², it is then tilted into a dumping position and 40 its load discharged on the embankment at that side of the ditch. The back and forth motion of the two operating chains results, therefore, in an alternate filling and dumping of the two buckets, one bucket being 45 caused to fill while the other is being carried to starting point, and vice versa, and each bucket being caused to dump at the same time that the other bucket arrives at the starting point of its course of travel. 50

Throughout the entire range of travel of the buckets the two operating chains are held in alinement with the runway, so that the pull exerted on each bucket is always in a straight line, and never in a direction 55 oblique or at an angle to the direction of the runway. In this way side draft on the bucket is completely eliminated, and each bucket is enabled to round a curve or turn a corner without encountering heavy side draft, such as was heretofore more or less true of machines of this kind. The chains, as well as the buckets, are supported for traveling movement in the tracks of a double runway, and thus the travel of the two operating chains is in the same direction along 60 the same line as that of the buckets. The operating chains or other flexible connections never pull at an angle to the direction of the runway, and consequently the buckets are never caused to bind or run hard in the 65 runway, as was heretofore more or less the case with excavators of this kind.

It will also be seen that by the provision of the booms or pivoted braces P and Q, a portion of the weight of the runway structure is supported directly upon the frame of the machine. The outer ends of these members P and Q are pivotally secured respectively to the outer ends of the runway sections G and H, while their inner ends are 70 pivotally secured to the bracket plate d, or in any other suitable manner to the upper end of the superstructure D of the frame of the excavator. Thus when the runway structure is raised and lowered, the entire weight 75 thereof is not carried up and down, as a portion of the weight of the members P and Q is supported directly upon the frame of the excavator. In addition, the runway structure is rendered much stronger and 80 more reliable in use, inasmuch as the draft or pull of the operating cables J and L is exerted in a direction lengthwise of the members P and Q, so that the pull of each cable does not tend to strain or break the 85 outer ends of the runway. In other words, the pull of each cable is resisted and taken up entirely by the endwise thrust or bracing effect of the members P and Q, one at each 90 side of the machine, so that no straining effect is exerted by these cables upon the upper ends of the runway. With the arrangement thus described, it will be seen that the raising and lowering of the runway is 95 accompanied by a slight swinging movement 100 of the outer sections thereof about their pivots g and h, due to the fact that the members P and Q swing about pivots or axes at their inner ends. Preferably the said braces or members P and Q are equipped with 105 tracks extending in continuation of the tracks g² and h², whereby the wheels i' and 110 the chains to which they are attached are supported after leaving the upper ends of 115 the runway. As shown in Fig. 1, the buckets are at the left of the excavator, and consequently the operating chains for the said buckets have been carried around the upper 120 end of the runway G, and the wheels i' are shown resting upon the said tracks with 125 130

which the member P is equipped. When the buckets are caused to travel to the other side of the excavator, then the operating chains and the said wheels i travel upwardly and around the upper end of the runway section H, and are carried onto the tracks with which the member Q is equipped. In this way the operating chains and the wheels and the spreaders i are supported and prevented from sagging whenever they leave the upper ends of the runway.

I do not limit myself to the exact construction shown and described.

What I claim as my invention is:

1. In an excavator, a pivoted runway, an excavating bucket adapted to travel back and forth thereon, a flexible connection for operating the bucket on the runway, extending a distance along the runway, in front

and rear of the bucket, wheels on said flexible connection, traveling on said runway, cables connected with said connection, and drums for operating said cables.

2. In an excavator, a pair of oppositely facing and alternately operating buckets, a runway for said buckets, wheels for said buckets, a pair of flexible connections for operating said buckets in a back and forth manner upon the said runway, wheels on said flexible connections, traveling on said runway, cables attached to the ends of said connections, and drums for operating said cables.

3. In an excavator, an excavating bucket, a runway therefor, a pair of parallel flexible connections for operating the bucket on the runway, spreaders for spacing the two flexible connections apart, means on said spreaders for engaging said runway, and means including cables and drums for operating said flexible connections to cause said buckets to travel back and forth on the runway.

4. In an excavator for making a ditch, an excavating bucket, a runway therefor adapted to be lowered into the ditch to determine the cross sectional contour thereof, a pair of flexible connections for operating said bucket on the runway, spreaders for spacing the two flexible connections apart, means on said spreaders for engaging said runway, and means including cables secured to the ends of said connections for operating the flexible connections to cause the bucket to travel back and forth on the runway from one side of the ditch to the other, said spreaders supporting the said flexible connections.

5. In an excavator, a double track runway, a pair of chains spaced apart and provided outside thereof with wheels traveling in the tracks of said runway, and an excavator bucket pivoted upon and disposed between said chains, together with means for tilting the bucket to dumping position, and cables and drums for operating said chains.

6. In an excavator, an excavating bucket,

a pivoted runway therefor, a brace pivoted to the outer end of said runway, means for pivotally supporting the inner end of said brace, a flexible connection for operating the bucket on the runway, and a track on 76 said brace for supporting said flexible connection when the bucket moves to the outer end of the runway.

7. In an excavator, a runway, means for moving the same up and down, an excavating bucket adapted to travel back and forth on the runway, a brace for the outer end of the runway, a flexible connection for operating the bucket, and a track on the said brace for supporting the said flexible connection when the bucket moves to the outer 75 end of the runway.

8. In an excavator, a runway, a bucket adapted to travel back and forth thereon, a flexible connection for operating said bucket, 85 a frame, a brace connecting the outer end of the runway with said frame, devices on said flexible connection to guide the same along the said runway, and means on said brace for guiding said devices to support the 90 flexible connection thereon when the bucket moves to the outer end of the runway.

9. In an excavator, a runway adapted to enter the ditch to determine the cross sectional contour thereof, a bucket adapted to 95 travel back and forth on said runway, a flexible connection for operating the bucket, devices on the flexible connection for guiding the same along the runway, braces for the outer ends of the runway, and means on 100 said braces for guiding said devices along the length thereof to support the said flexible connection whenever the movement of the bucket is such as to cause a portion of the said connection to leave either end of the 105 runway.

10. In an excavator, a runway adapted to enter the ditch to determine the cross sectional contour thereof, a pair of oppositely facing buckets adapted to travel back and 110 forth on said runway, means for moving the runway up and down, a flexible connection for operating the buckets on the runway, swinging braces extending to the outer ends of said runway, devices on said flexible connection for guiding the same along the runway, and means on said braces for engaging said devices to support the opposite end portions of said flexible connection thereon.

11. In an excavator, a runway having a 120 bend therein, an excavating bucket on said runway, a flexible draft connection extending from the bucket along the runway, a series of supports secured to said connection, each said support engaging the runway to 125 maintain said connection in the direct line of draft while passing around said bend, means attached to said connection to pull the bucket along the runway, devices for causing a discharge of the load when the bucket 130

reaches a predetermined point on the runway, and instrumentalities for drawing the bucket back in the opposite direction, said bucket having the same path of travel for both movements thereof, pivoted extensions of said runway, braces pivoted to said extensions, adapted to receive said supports, a stationary support to which the inner ends

of said braces are pivoted, and means for raising and lowering said runway. 13

Signed by me at Chicago, Illinois, this 17th day of December, 1910.
